RADIO OR THE LIKE

Henry Petersen, Omaha, Nebr., assignor to Textron Electronics, Inc., Providence, R.I., a corporation of Delaware

Filed Aug. 17, 1959, Ser. No. 57,191

Term of patent 3½ years

(Cl. D56—4)

Figure 1 is a front perspective view of a radio embodying my new design;

Figure 2 is a top plan view;

Figure 3 is a fragmentary side elevational view;

Figure 4 is a fragmentary side elevational view showing the side opposite that shown in Figure 3; and

Figure 5 is a fragmentary sectional view taken on the line 5—5 of Figure 1.

The stippling indicates contrast.

The dominant features of my design reside in the portion shown in full lines.

I claim:

The ornamental design for a radio or the like, as shown and described.
